ment Company, San Francisco, Calif., a corpo-
ration of Delaware

Application March 18, 1944, Serial No. 527,381

7 Claims. (Cl. 62—1)

The present invention relates to a system for supplying liquefied gas from a storage container to a second container and more particularly to a system for supplying liquefied petroleum gas from a service truck to small domestic supply tanks.

In those localities where natural and/or manufactured gas is not available for domestic heating or other purposes, it has become common practice to utilize liquefied petroleum gases stored in small pressure containers, vapor from the top of the container being supplied under pressure to conduits leading to various heating apparatus. The capacity of the domestic containers generally employed is sufficient for approximately 2 months or more supply under average conditions. At the end of this period it is necessary to either refill the domestic container in place or replace it with a container which has been refilled at a depot by the distributor. Since the handling and transportation of these small cylinders under such conditions is, under certain conditions, both an expensive and inefficient procedure, various arrangement have been devised to permit refilling of the cylinders in place from a supply tank carried on a truck. However, as the domestic tank is filled from the supply tank, the pressure in the domestic tank rapidly increases to a point whereat it equals or exceeds the pressure in the supply tank, thus preventing further flow to the domestic tank. In order to overcome this difficulty, it has become common practice to employ a pressure pump mounted on the service truck in order to fill the domestic tank to its rated capacity. Pressure pumps adapted to handle liquefied gases are in many instances, however, complicated and expensive and require constant maintenance.

It is an object of the present invention to provide an arrangement whereby transfer of liquefied gas from a supply tank to a second tank may be made without the use of pumping equipment. A further object is to provide such an arrangement which is particularly adapted for servicing of domestic fuel tanks from a supply tank mounted on a service truck. Another object is to provide an arrangement utilizing heat generated by an internal combustion engine for effecting such transfers. Still another object is to provide equipment adapted to efficiently increase the pressure in a liquefied gas storage tank by utilizing heat generated by an internal combustion engine to vaporize a portion of the liquefied gas in a container and return the vapors to the vapor space above the liquid level in the container. Other objects, together with some of the advantages to be derived in utilizing the present inven-

tion, will become apparent from the following detailed description thereof, taken together with the accompanying drawings forming a part of the specification and wherein

5 Fig. I is a schematic view showing the general arrangement of the invention;
Fig. II is an elevation, partly in section, illustrating a liquefied gas storage container according to the invention;
10 Fig. III is a sectional end elevation through III—III of Fig. II;
Fig. IV is an end elevation, partly in section, through IV—IV of Fig. II.
Referring to Fig. I, a conventional domestic 15 delivery truck 1 provided with containers as at 2 for various products, is also provided with a pressure tank 3 containing liquefied petroleum gas, such as, for example, propane, butane, isobutane or various mixtures of the same. A heat exchanger 7, which is described in detail below, is in flow communication with an intake conduit 8 including valve 10 leading from the hot water outlet 50 of the truck engine cooling system and a return conduit 9 leading from heat exchanger 7 to the engine cooling system. A conduit 4 leads from the interior of pressure tank 3 and may be connected with the discharge outlet of a domestic supply tank as at 5. The quantity of liquefied 20 gas passed into tank 5 may be determined by means of the weight differential between the tank when empty and full, as determined by scale 6 upon which tank 5 may be placed.

In Figs. II and III, pressure tank 3 is supported by cradle 22 which is in turn supported on skids 35 11 and 12 by means of a plurality of steel leg plates as at 14, 15, 16, 18 and 21 (20 and 21 of Fig. IV). Heat exchanger 7 is positioned beneath tank 3 and is supported by conduits 23 and 25. Hot water conduit 8 leading to heat exchanger coil 10 and return conduit 9 both pass through the end wall of heat exchanger 7 as shown. Vapor conduits 23 and 25 pass from the top of heat exchanger 7 through the center of tank 3 and terminate at a point near the top of tank 3 in the interior thereof. A second pair of conduits 40 24 and 26 are provided around conduits 23 and 25 respectively, being welded to the same at the top end thereof and welded to tank 3 at the bottom thereof, thus providing an air space open to the atmosphere between the inner and outer conduits.

45 A well 28 is provided in the bottom of tank 3 at or near the center thereof. Arcuate conduit 27 is in flow communication with well 28 and the 50 interior of heat exchanger 7. Channel iron cross

member 17 serves as a guard for arcuate conduit 27.

Conduit 32 extends to a point near the bottom of tank 3 and passes out an end wall of tank 3 through a threaded reducing connection at 33. The external extension of conduit 32 leads to valve 34 which is in turn in flow communication with conduit 35 and threaded connection element 36. Conduit 37 including pressure gauge 38 is in flow communication with the interior of tank 3 and pressure relief valve 39 provided with spring 40 normally urging valve element 41 to a closed position. Conduit 40 leads from pressure relief valve 39 to a diaphragm actuated valve 44 in conduit 8. Valve actuating rod 43 is normally urged upwardly against diaphragm 41 by means of spring 42, valve 44 being open under these conditions. Conduit 40 leads to a pressure chamber in which diaphragm 41 is disposed.

A conventional measuring rod for liquefied petroleum gases is provided at 29 in order to determine the quantity of material within tank 3. Tank 3 is also equipped with customary safety devices such as a pressure relief valve 60 and fusible plugs at 31 and 61.

The unit operates as follows: liquefied gas passes into the bottom of heat exchanger 7 through conduit 27 from tank 3 and finds its own level in conduits 23 and 25. Hot water passing through conduits 8 and 9 vaporizes the part of the liquefied petroleum gas in heat exchanger 7, the vapors passing through conduits 23 and 25 to the vapor space above the liquid level in tank 3. The increased pressure in tank 3 forces liquefied petroleum gas out of tank 3 through conduit 32, valve 34 and conduit 35, which is connected to conduit 4 (Fig. I) leading to the container which it is desired to fill. Conduit 32 is utilized additionally to refill pressure tank 3.

In the event that the pressure in tank 3 exceeds the desired maximum, pressure relief valve 39, which has been previously set to operate at this maximum, opens and permits vapor under pressure to enter the pressure chamber above diaphragm 41, depressing the diaphragm and forcing rod 43 downwardly to close valve 44. When using propane, for example, it has been found desirable to set pressure relief valve 39 to open at approximately 240 p. s. i. With valve 44 closed, flow of hot water to heat exchanger 7 is prevented, thus avoiding any further increase in pressure in tank 3. When the pressure in tank 3 drops below the predetermined maximum, spring 46 acts to close pressure relief valve 39. A small orifice 45 is provided in conduit 40, thus permitting vapor trapped in conduit 40 and the pressure chamber above diaphragm 41 to escape slowly. As soon as pressure relief valve 39 closes, the pressure above diaphragm 41 will begin to drop as a result of vapor leak through orifice 45 and when the pressure approaches atmospheric, spring 42 will operate to raise rod 43 and thus open valve 44.

The supply of heat to heat exchanger 7 may also be controlled manually through valve 10 which is accessible to the operator of the service truck.

A particular advantage of the servicing system described above lies in the fact that a pressure increase in tank 3 sufficient to overcome the static pressure in the customer's supply tank may be rapidly attained by heating only a small portion of the material from tank 3. In handling propane, for example, it has been found that the desired pressure in tank 3 is attained after sup-

plying hot water to heat exchanger 7 for a period of time of the order of ten minutes. This is an important factor in equipment of the type described, both from the standpoint of the short period of time required to develop the desired delivery pressure and because heating of the contents of the delivery tank is avoided. Any system which requires substantial heating of the entire contents of the supply tank in order to increase the pressure therein for deliveries, is inherently inefficient and undesirable for use in transfer operations of this type. When heated material is supplied to the customer's tank from the delivery tank, the pressure in the customer's tank rapidly increases to that of the delivery tank, thus preventing further flow of material to the customer's tank. The present arrangement overcomes these difficulties entirely, material being delivered to the customer's tank from the bottom of supply tank 3 at atmospheric temperatures and the desired pressure increase in supply tank 3 being attained without substantial heating of the contents thereof. The relatively small amount of liquefied gas which is contained in heat exchanger 7 is rapidly vaporized and the vapors passing through insulated conduits 23 and 25 immediately increase the pressure of the liquid contained in supply tank 3 without substantial heat exchange with the liquid content of tank 3.

Certain variations and modifications of the arrangement as shown which may be made without departing from the disclosed principles of operation and design, will be apparent to those skilled in the art. For example, the heat supply to heat exchanger 7 may be in the form of hot exhaust gases from the truck engine, or electrical heat energy may be supplied to immersion heaters disposed in the heat exchanger with the truck engine generator as a source of supply, or if necessary or desired for any reason, an independent source of heat energy may be provided. For most purposes and in consideration of the safety factors which must be considered in such equipment it is preferred to employ the arrangement disclosed, i. e. hot water from the engine cooling system as a source of heat energy for the heat exchanger.

Although conduits 23 and 25 are shown as being insulated from the contents of tank 3 by means of an air space and a second pair of conduits, the air space being open to the atmosphere, it will be appreciated that other means for insulating the vapor conduits may be employed. For example, a double walled conduit system as shown may be advantageously utilized and the space between each pair of conduits packed with a heat insulating material such as asbestos, rock wool, glass fiber, etc. Also, the space between each pair of conduits may be sealed at the bottom thereof and the air pumped out to provide vacuum insulation. Alternatively, single walled vapor conduits having a relatively great wall thickness and formed of a heat insulating material such as pressed asbestos and the like may be employed. In such instances it will be necessary to provide a pressure seal at the bottom of tank 3 at the point where the vapor conduits pass through the tank wall.

The invention claimed is:

1. In liquefied gas dispensing equipment of the class described, the combination comprising a pressure tight supply tank for liquefied gas, vaporizing means, flow communication means extending from said supply tank below the liquid level therein to said vaporizing means, flow communication means extending from said vaporizing

means through said supply tank and terminating at a point above the liquid level therein and means for withdrawing liquefied gas from said supply tank.

2. In liquefied gas dispensing equipment of the class described, the combination comprising a pressure tight supply tank for liquefied gas, a heat exchanger disposed beneath said supply tank, gravity flow communication means extending from said supply tank below the liquid level therein to said heat exchanger conduit means extending from said heat exchanger through said supply tank and terminating at a point above the liquid level in said supply tank, conduit means having a larger diameter and disposed concentric with said first named conduit means extending from the bottom of said supply tank and joined to said first named conduit means at the upper end thereof, said second named conduit means defining an annular insulating space open to the atmosphere between said first and second named conduit means, means for supplying heat to said heat exchanger and means for withdrawing liquefied gas from said supply tank.

3. In liquefied gas dispensing equipment of the class described, the combination comprising a pressure tight supply tank for liquefied gas, a heat exchanger disposed beneath said supply tank, a well in the bottom of said supply tank, conduit means extending in flow communication from said well to said heat exchanger, conduit means extending in flow communication from said heat exchanger through said supply tank and terminating at a point above the liquid level in said supply tank, conduit means having a larger diameter and disposed concentric with said first named conduit means extending from the bottom of said supply tank and joined to said first named conduit means at the upper end thereof, said second named conduit means defining an annular insulating space open to the atmosphere between said first and second named conduit means, means for supplying heat to said heat exchanger and delivery conduit means extending from a point within said supply tank below the liquid level therein to a point external to said supply tank.

4. In liquefied gas dispensing equipment of the class described, the combination comprising a pressure tight supply tank for liquefied gas, a heat exchanger, gravity flow communication means extending from said supply tank below the liquid level therein to said heat exchanger, thermally insulated flow communication means extending from said heat exchanger through said supply tank and terminating at a point above the liquid level therein, conduit means for withdrawing liquefied gas from said supply tank, conduit means leading in flow communication from a source of heated fluid to said heat exchanger, a valve including an actuating element in said last named conduit means and pressure responsive means adapted to actuate said actuating element to close said valve when the pressure in said supply tank reaches a predetermined maximum.

5. In liquefied gas dispensing equipment of the class described, the combination comprising a pressure tight supply tank for liquefied gas, a heat exchanger, means for supplying heat to said heat exchanger, gravity flow communication means extending from said supply tank below the liquid level thereof to said heat exchanger, a pair of thermally insulated conduits extending in flow communication with said supply tank and with said heat exchanger through said supply tank near opposite ends thereof and terminating at points above the liquid level in said supply tank, said gravity flow communication means being disposed between said pair of thermally insulated conduits and means for withdrawing liquefied gas from said supply tank.

6. In liquefied gas dispensing equipment of the class described, the combination comprising a service truck including a liquid cooled internal combustion engine, a pressure tight supply tank for liquefied gas mounted on said service truck, a heat exchanger disposed beneath said supply tank, conduit means carrying hot liquid coolant from said internal combustion engine to said heat exchanger, conduit means returning liquid coolant from said heat exchanger to said internal combustion engine, gravity flow communication means extending from said supply tank below the liquid level therein to said heat exchanger, thermally insulated flow communication means extending from said heat exchanger through said supply tank and terminating within said supply tank at a point above the liquid level therein and conduit means for withdrawing liquefied gas from said supply tank.

7. In liquefied gas dispensing equipment of the class described, the combination comprising a service truck including a liquid cooled internal combustion engine, a pressure tight supply tank for liquefied gas mounted on said service truck, a heat exchanger disposed beneath said supply tank, conduit means carrying hot liquid coolant from said internal combustion engine to said heat exchanger, a valve including an actuating element in said conduit means, pressure responsive means in flow communication with said supply tank adapted to actuate said actuating element to close said valve when the pressure in said supply tank reaches a predetermined maximum, conduit means returning liquid coolant from said heat exchanger to said internal combustion engine, a well in the bottom of said supply tank, gravity flow communication means between said well and said heat exchanger, a pair of thermally insulated conduits extending in flow communication with said supply tank and said heat exchanger through said supply tank near opposite ends thereof and terminating at points above the liquid level in said supply tank, said well in the bottom of said supply tank being disposed between said pair of thermally insulated conduits and means for withdrawing liquefied gas from said supply tank.
